UNITED STATES PATENT OFFICE.

JOSEPH E. RANDA, OF HIGHLAND PARK, MICHIGAN.

SASH-FASTENER.

1,086,462.

Specification of Letters Patent. Patented Feb. 10, 1914.

Application filed June 30, 1913. Serial No. 776,570.

To all whom it may concern:

Be it known that I, JOSEPH E. RANDA, a citizen of the United States, residing at Highland Park, in the county of Wayne 5 and State of Michigan, have invented a new and useful Sash-Fastener, of which the following is a specification.

My invention relates to sash fasteners; and the object is to provide a device which 10 when applied to a window sash may hold the window sufficiently open for ventilation but will not permit unwarranted further opening of the window from the outside by burglars or other intruders. The device 15 may also be used as a substitute for sash weights, and will hold the window closed when so desired; so it really serves the purposes of three devices, namely to hold the sash raised, hold it raised and locked, and 20 hold it locked when closed.

In the accompanying drawing, Figure 1 is an inner side elevation of a portion of a window sash and the adjacent frame, the latter in section as on the line *a—a* Fig. 4, 25 with my invention applied thereto. Fig. 2 is a portion of a window frame with the sash removed, showing the perforated metal strip secured on the frame for the locking device to engage. Fig. 3 is an edge view 30 of the sash provided with the locking means of the device and adapted to slide against the strip in Fig. 2. Fig. 4 is a horizontal section of a window frame and a pair of sash hung therein, the sash having the locking 35 device being intersected substantially on the line *b—b* Fig. 3. Fig. 5 is a bottom view of the device proper removed from the sash and having its operating button removed. Fig. 6 is a section on the line *c—c* Fig. 5. 40 Fig. 7 is a detail side view of the screw stud 19 in Figs. 5 and 6, but it also shows the shape of the screw 22 in Fig. 4.

Referring to the drawing by reference numerals, 1 designates the frame, 2 and 2^a the parting strips, and 3 the inside stop of a window opening. Slidably fitted between said strips 2 and 2^a is the upper window sash 4, having the glass 5, while between the stop 3 and the parting strip 2 is slidably fitted 50 the sash 4^a, having the glass 5^a and constituting the lower and inner sash of the window. As both sashes are or may be equipped with the same kind of fasteners, only one fastener need to be described, and 55 the same is as follows: As a necessary part of the device when it is properly made, a

metal strip or plate 7 is secured by screws 6 upon the frame. Said plate may have teeth or any suitable kind of indentures, but in the drawing I have shown plain holes 60 8, for the locking bolt 9 to engage. Said bolt is slideable in a hole in a cylindrical body or casing 10, which is adapted to go into a cylindrical hole in the edge of the sash and is provided with flanges 11 having holes 65 12 for screws 13, which hold the device in place. Said cylinder may have one side slightly flattened as at 14, but otherwise the cylinder is solid except for the holes bored in it. Said holes are, one for the bolt 9 70 and a spring 15 partly compressed between the end of the bolt and the bottom of the hole; another hole is for the rack bar 16, which slides across the locking bolt and is geared to it by a cog-wheel or pinion 17; 75 the latter is loosely fitted in a hole 18 and rotates on a screw 19 (see Figs. 6 and 7), which screw has a shoulder 20 to limit its forward progress and to hold the screw steady as a stud on which the pinion rotates 80 guarded by the head 21 so it can not escape from the stud. Another screw, 22, similar to the screw 19 in Fig. 7, is threaded at 23 into one end of the rack 16, and is provided with a head 24 which serves as a press-button, and is slideable in a thimble 25, which is inserted in a cylindrical hole in the inner 85 side of the sash and is provided with ears 26 secured by screws 27 to the sash.

On ordinary windows the locking device 90 is inserted in the sash about twenty-two inches from the bottom of the lower sash, and a similar distance from the top of the upper sash to the fastener used on the upper sash, so as to bring the locking devices out 95 of reach by a person's hand standing outside the window when the sashes are partly opened for ventilation above and below them.

If the sashes are hung by the cords and 100 weights, such hanging does not interfere with this fastener, and if there are no sash weights, my device will effectively hold the sashes at any desired elevation, and will also lock them in closed position.

Whenever the sash is to be moved up or down, the operator, being inside the room having the window, simply presses on the button 24 and the rack 16 will rotate the pinion 17 and thereby retract the bolt 9 110 from the strip 7 on the frame.

In one side of the thimble 25 is a hole

28 for the insertion of a wire peg or key 29 (see Figs. 1 and 4). Said key serves to hold the press button depressed and thereby by the locking device idle or unlocked while 5 the windows are being washed, or when it is otherwise desired to have the windows for a time moving freely. Said key 29 is suspended by a cord or chain 30 near the lock, so as not to get lost, but to be handy 10 whenever wanted.

The screw heads 21 and 24 are each provided with a notch 31 for a screw-driver to take hold in when the screws are to be removed, or when they are to be inserted 15 and screwed tight, in assembling the parts of the mechanism.

What I claim as new, and wish to secure by Letters Patent, is:

1. The combination with a window frame, 20 of a serrated or perforated plate secured thereon, a sash arranged to move close to said plate, a metal casing carried by the sash, a cog-pinion mounted in the casing, two racks meshing with the pinion, one of 25 said racks having one end arranged to enter into the plate, a spring acting on the rack to push it toward the plate, the other rack having at one end a push-button operable from the inner side of the sash and 30 located out of sight from outside the window and so far from the end of the sash, that is to be opened, that it can not be reached and operated from without the window when the window is partly opened for 35 ventilation.

2. The combination with a window frame, of a serrated or perforated plate secured thereon, a sash arranged to slide along said plate, a metal casing carried by the 40 sash, a cog-pinion mounted in the casing, two racks meshing with the pinion, one of said racks arranged to enter into the plate, a spring pushing said rack toward the plate; the other rack having at one end a 45 push-button operable from the inner side of the sash and concealed in a cavity therein and located so far from the opening end of the sash that it can not be reached and operated from without the window when the latter is partly opened for ventilation; and 50

means for locking said push-button in depressed position when so desired.

3. The combination with a window frame and a vertically disposed serrated or perforated strip secured thereon, of a sash guided 55 to slide with one edge along said strip and having in said edge a cylindrical cavity, and communicating therewith a second cylindrical cavity in the inner side of the sash; a metallic cylindrical casing inserted in the 60 first mentioned cavity and secured to the sash, a spring-pressed bolt slideable in the casing and arranged to enter into the strip, said bolt having at one side cogs, a stud in the casing, a cog pinion mounted on the 65 stud and meshing with said cogs, a short rack slideable in the casing in crossing position to the bolt and engaging the pinion, a guiding metal thimble in the cavity of the inner side of the sash, a push-button slideable 70 wholly within said thimble, and having a stem threaded into the adjacent end of the short rack.

4. The combination with a window frame and a vertically disposed perforated strip 75 secured thereon, of a sash guided to slide with one edge along said strip and having in said edge a cylindrical cavity, and communicating at right angles therewith a second cylindrical cavity in the inner side of 80 the sash; a metallic cylindrical casing inserted in the first-mentioned cavity and secured to the sash, a spring-pressed bolt slideable in the casing and arranged to enter into the perforations of the strip, said bolt having at one side cogs, a stud in the 85 casing, a cog-wheel mounted on the stud and meshing with the cogs of the bolt, a short rack sliding in the casing in closing position to the spring-pressed bolt and meshing 90 with the cog-wheel, a push-button movable wholly within the second cavity of the sash and operatively connected with the short rack.

In testimony whereof I affix my signature, in presence of two witnesses.

JOSEPH E. RANDA.
